UNITED STATES PATENT OFFICE

149,613

DESIGN FOR A POKER CHIP

Charles E. Caestecker, Kenilworth, Ill., assignor
to American Molded Products Co., Chicago, Ill.,
a corporation of Illinois

Application January 25, 1947, Serial No. 136,437

Term of patent 14 years

(Cl. D34—5)

To all whom it may concern:

Be it known that I, Charles E. Caestecker, a citizen of the United States and a resident of Kenilworth, in the county of Cook and State of Illinois, have invented a certain new, original, and ornamental Design for a Poker Chip, of which the following is a specification, reference being had to the accompanying drawing, forming a part thereof.

Figure 1 is a perspective view of the poker chip, showing my new design; and

Figure 2 is a staggered sectional view taken substantially as indicated at line 2—2 on Figure 1.

I claim:

The ornamental design for a poker chip, substantially as shown.

CHARLES E. CAESTECKER.
